UNITED STATES PATENT OFFICE

JOHN B. HOLTZ, OF LOS ANGELES, CALIFORNIA, ASSIGNOR TO INVENTION DEVELOPMENT CORPORATION, OF CARSON CITY, NEVADA

DESIGN FOR AN ADVERTISING PEDESTAL FOR CLOCK AND WEIGHING MACHINE

Application filed September 9, 1929. Serial No. 32,702. Term of patent 14 years.

To all whom it may concern:

Be it known that I, JOHN B. HOLTZ, a citizen of the United States, and a resident of Los Angeles, Los Angeles County, California, have invented a new, original, and ornamental Design for Advertising Pedestal for Clock and Weighing Machine, of which the following is a specification, reference being had to the accompanying sheet of drawings, forming a part hereof. In the drawings—

Figure 1 is a front elevation of an adver-

tising pedestal for clock and weighing machine, showing my new design; and

Figure 2 is a cross sectional view through said pedestal to show its triangular form.

The panels indicated are provided for advertising displays.

I claim:

The ornamental design for an advertising pedestal for clock and weighing machine, substantially as shown and described.

JOHN B. HOLTZ.
